CLAIM

The ornamental design for non-spill drinking lid, as shown and described.

DESCRIPTION

FIG. 1 is a perspective view of the rear, top, and right side of the non-spill drinking lid;

FIG. 2 is a perspective view of the rear, top, and left side of the non-spill drinking lid;

FIG. 3 is a top view of the non-spill drinking lid;

FIG. 4 is a rear view of the non-spill drinking lid;

FIG. 5 is a left side view of the non-spill drinking lid; and,

FIG. 6 is a bottom view of the non-spill drinking lid.
The portions of the non-spill drinking lid shown in broken lines form no part of the claimed design.

1 Claim, 5 Drawing Sheets
